UNITED STATES PATENT OFFICE.

THOMAS R. ERNEST, OF CHICAGO, ILLINOIS, ASSIGNOR TO CHICAGO APPARATUS CORPORATION, OF CHICAGO, ILLINOIS, A CORPORATION OF ILLINOIS.

GAS-TESTING MACHINE.

Application filed March 3, 1921. Serial No. 449,443.

To all whom it may concern:

Be it known that I, THOMAS R. ERNEST, a citizen of the United States, and a resident of the city of Chicago, county of Cook, and State of Illinois, have invented certain new and useful Improvements in Gas-Testing Machines, of which the following is a specification.

My invention relates to gas testing mechanisms, and it has for its principal object the provision of a new and improved form and arrangement of parts by which gases may be tested at intervals throughout the period of their production for the purpose of proving their purity prior to their being led to the ordinary tank for storage and whereby assurance may be had that the gas passing to the tank is not an explosive mixture liable to cause a serious explosion upon the introduction of a spark from any source. It is another object of my invention to provide automatically acting means for throwing the gas producing means out of operation if for any reason a quantity of explosive gas may be produced.

Other objects will appear hereinafter.

The invention consists in the combinations and arrangements of parts hereinafter described and claimed.

The invention will be best understood by reference to the accompanying drawings forming a part of this specification, and in which,

Fig. 1 is a diagrammatic view showing one form of my improved mechanism installed in connection with a gas producing means, and,

Fig. 2 is a vertical cross section through one of the testing devices employed.

Referring to the drawings, 5 indicates a direct current generator connected by lead wires 6 and 7 with an electrolyzer 8 of any approved type by which gases are produced. The electrolyzer shown comprises a partition 9 indicated by dotted lines by which the gases generated at the poles of the cell are kept out of contact with each other for delivery through the pipes 10 and 11.

For testing the gases being delivered from the electrolyzer 8, I have provided auxiliary pipes 12 and 13 of a small size leading from opposite sides of the curtain or partition 9, such pipes being arranged to carry a relatively small proportion of the gas being produced to receptacles 14 and 15 respec-

tively, which are mounted upon a board 16 in convenient position. Each of the receptacles 14 and 15 is in constant communication with the atmosphere through a stub pipe 17, whereby the gas within the receptacle is maintained at substantially atmospheric pressure. Means is provided for producing a spark at intervals within each of the receptacles 14 and 15. As will be readily understood, if an explosion takes place within the receptacle when the spark is produced, such occurrence indicates that an explosive mixture is being delivered to the storage tank,—that is to say, that an objectionable mixing of gases is occurring. Upon such indication, the electrolyzer or other gas producing means is to be thrown out of operation until the defect, by reason of which the mixing takes place, can be remedied.

In the construction shown, I have provided means adapted automatically to throw the electrolyzer out of operation upon the occurrence of an explosion within one of the receptacles 14 and 15. In the construction shown, the means for throwing the gas producing apparatus out of operation comprises a switch 18 interposed in the electric circuit connecting the generator 5 with the electrolyzer 8, a condenser 19 being connected across the gap of the switch for reducing the sparking upon the opening of the switch as hereinafter described. A spring 20 is connected with the switch 18 adapted normally to hold the switch open, but adapted to yield to permit the closing of the switch for starting the apparatus in operation.

The switch is held in operative closed position by means of an electro-magnet 21 which operates upon an armature 22 carried by the switch 18 for holding the switch closed against the action of the spring. The electro-magnet 21 is energized by a shunt current provided by a circuit 23 comprising electric switches 24 and 25 connected in series in said circuit. Means is provided adapted upon an explosion in one of the receptacles 14 and 15 to open the corresponding switch 24 or 25 for breaking the circuit 23 and thus de-energizing the magnet 21 so as to permit the spring 20 to open the switch 18 for stopping the operation of the gas producing apparatus.

The means in the construction shown for producing a series of sparks intermittently

within the receptacles 14 and 15 is in the form of a transformer comprising a primary coil 26 and a secondary coil 27, the primary coil being connected by means of a circuit 28 across the main circuit from the generator 5. The circuit 28 comprises a heating element 29 of any suitable type, being shown in the form of a lamp adapted to be heated by the current passing through the circuit 28. Adjacent to the lamp 29, I have provided a switch comprising a bi-metal arm 30 the two parts of which are connected by a series of rivets 31 so that upon the heating of the arm the arm as a whole will curl for lifting the free end out of operative engagement with the contact member 32 of the switch. It is designed that the two parts of the arm 30 shall be made of iron and zinc, or of any other two metals which have a materially different coefficient of expansion, as is fully appreciated in connection with thermostatic regulators of this type. It will be understood that upon the breaking of the circuit 28 by the movement of the arm 30, the heating element 29 will be thrown out of operation, whereupon the arm 30 is permitted to cool and to straighten out for re-establishing the circuit. The arrangement is preferably to be such that the circuit will be opened at intervals of one to three minutes.

The secondary coil 27 is connected by means of a wire 33 with the metal casing of one of the receptacles 14 and 15, in which metal casing I have provided a spark plug 34 of any suitable type, such spark plug being connected by means of a wire 35 with the metal casing of the other receptacle. A wire 36 is provided, in turn, for connecting the coil 27 with a spark plug 37 mounted in the casing with which the wire 35 is connected. It is thus seen that the spark plugs 34 and 37 are connected in series with the secondary coil 27 whereby, upon the breaking of the circuit through the primary coil 26 as above described, a high tension induced current is produced in the secondary circuit causing a spark at each of the plugs 34 and 37 within the receptacles 14 and 15.

Coming now to the description of one of the receptacles 14 and 15 and the switches 24 and 25 which are to be operated in connection therewith, (see Fig. 2) 38 indicates a resilient diaphragm preferably formed from a thin sheet of metal mounted in the side wall of the casing of the receptacle 14, such diaphragm constituting a portion of such side wall. Mounted upon the diaphragm 38, I have provided an arm or lug 39, preferably of fiber, such arm being in contact at its outer end with one arm of the switch 24 which is shown in the form of a bell crank lever pivotally mounted upon a fiber post 40 carried by the board 16. A spring 41 is provided adapted normally to hold the switch 24 in the position shown in

solid lines in said Fig. 2, with one of its arms in operative engagement with a contact 42 supported by a fiber post 43. The contact 42 and the bell crank lever of the switch are connected respectively with the leads of the circuit 23.

Inasmuch as the receptacle 15 and cooperating parts are similar, it is believed to be unnecessary to describe the same in detail.

Upon an explosion within one of the receptacles 14 and 15, the diaphragm 38 is bulged outwardly, serving to swing the switch member 24 in counterclockwise direction in Fig. 2 for breaking the operative engagement between such switch member and the contact 42. The circuit being thus temporarily broken through the leads 23, the spring 20 is enabled to move the switch arm 18 toward the right in Fig. 1 for opening the main circuit and throwing the electrolyzer out of operation and thus discontinuing the flow of the gas to the receptacles 14 and 15 through the pipes 12 and 13. In each of the receptacles 14 and 15, I have constructed the outer face in the form of a glass plate 44 so that an operator may be able to see the effect of a very weak explosion which might not be of sufficient force to open the switch as above described.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention, what I claim as new and desire to secure by Letters Patent is:—

1. In combination, a receptacle, means for causing a flow of gas through said receptacle at substantially atmospheric pressure, and means for producing a spark at intervals within said receptacle.

2. In combination, a receptacle provided with an opening to the air, means for delivering gas to said receptacle, and means for producing a spark at intervals within said receptacle while open to the air.

3. In combination, a receptacle, means for causing a constant flow of gas through said receptacle, and means for producing a spark at intervals within said receptacle.

4. In combination, a receptacle open constantly to the air, means for causing a constant flow of gas through said receptacle, and means for producing a spark at intervals within said receptacle.

5. In combination, means for producing gas, a receptacle, means for causing a relatively small proportion of said gas to have a constant flow through said receptacle, and

means for producing a spark at intervals within said receptacle.

6. In combination, means for producing gas, a receptacle, means for causing a relatively small proportion of the gas produced to flow through said receptacle at substantially atmospheric pressure, and means for producing a spark at intervals within said receptacle.
- 10 7. In combination, a receptacle, means for causing a flow of gas through said receptacle at substantially atmospheric pressure, means for producing a spark at intervals within said receptacle, and means actuated by an explosion of the gas within said receptacle for shutting off the flow of gas to the receptacle.

8. In combination, means for producing gas, a receptacle open constantly to the air, means for causing a relatively small proportion of the gas produced to have a constant flow through said receptacle, means for producing a spark at intervals within said receptacle, and means actuated by an explosion of the gas within said receptacle for shutting off the flow of gas to the receptacle.

9. In combination, means for producing gas, a receptacle, means for causing a relatively small proportion of the gas produced to flow through said receptacle at substantially atmospheric pressure, means for producing a spark at intervals within said receptacle, and means actuated by an explosion of the gas within said receptacle for throwing the gas producing means out of operation.

10. In combination, means for producing gas, a receptacle, means for causing a relatively small proportion of the gas produced to flow through said receptacle at substantially atmospheric pressure, means for producing a spark at intervals within said receptacle, and means operated by the pressure within said receptacle upon an explosion of gas therein for throwing said gas producing means out of operation.

11. In combination, a receptacle having a portion of its wall in the form of a yielding diaphragm, means for causing a flow of gas through said receptacle at substantially atmospheric pressure, means for producing a spark within said receptacle at intervals, and means actuated by the movement of said diaphragm upon an explosion within said receptacle for shutting off the flow of gas to said receptacle.

12. In combination, means for producing gas, a receptacle having a portion of its wall in the form of a yielding diaphragm, means for causing a relatively small proportion of the gas produced to flow through said receptacle at substantially atmospheric pressure, means for producing a spark at intervals within said receptacle, and means actu-

ated by the movement of said diaphragm upon an explosion within said receptacle for throwing the gas producing means out of operation.

13. In combination, a receptacle, means for causing a flow of gas through said receptacle at substantially atmospheric pressure, means for producing a spark at intervals within said receptacle, an electric circuit by which the flow of gas is controlled, 70 a switch in said circuit, and means actuated by an explosion of gas within said receptacle for operating said switch for shutting off the flow of gas to said receptacle.

14. In combination, means for producing gas, a receptacle, means for causing a relatively small proportion of the gas produced to flow through said receptacle at substantially atmospheric pressure, means for producing a spark at intervals within said receptacle, an electric circuit by which the operation of said gas producing means is controlled, a switch in said circuit, and means actuated by an explosion of gas within said receptacle for operating said switch 80 for throwing said gas producing means out of operation.

15. In combination, a receptacle having a portion of its wall in the form of a yielding diaphragm, means for causing a flow of 95 gas through said receptacle at substantially atmospheric pressure, means for producing a spark within said receptacle at intervals, an electric circuit by which the flow of gas to said receptacle is controlled, a switch in said 100 circuit, and means actuated by the movement of said diaphragm upon an explosion within said receptacle for operating said switch for shutting off the flow of gas to said receptacle.

16. In combination, means for producing gas, a receptacle having a portion of its wall in the form of a yielding diaphragm, means for causing a relatively small proportion of the gas produced to flow through said receptacle at substantially atmospheric pressure, means for producing a spark at intervals within said receptacle, an electric circuit by which the operation of said gas producing means is controlled, a switch in 110 said circuit, and means actuated by the movement of said diaphragm upon an explosion within said receptacle for operating said switch for throwing the gas producing means out of operation.

17. In combination, an electrolyzer, a receptacle, means for causing a relatively small proportion of the gas produced in said electrolyzer to flow through said receptacle at substantially atmospheric pressure, means 125 for producing a spark at intervals within said receptacle, and means actuated by an explosion of the gas within said receptacle for throwing the electrolyzer out of operation.

18. In combination, an electrolyzer, a receptacle, means for causing a relatively small proportion of the gas produced in said electrolyzer to flow through said receptacle at substantially atmospheric pressure, means for producing a spark at intervals within said receptacle, an electric circuit with which said electrolyzer is connected for operating the same, an electric switch in said circuit, and means actuated by an explosion

of the gas within said receptacle for opening said switch for throwing the electrolyzer out of operation.

In testimony whereof I have signed my name to this specification in the presence of two subscribing witnesses.

THOMAS R. ERNEST.
